UNITED STATES PATENT OFFICE.

BERNARD T. PENNIG, OF ST. PAUL, MINNESOTA, ASSIGNOR TO PENN-GREG MFG. CO.,
OF ST. PAUL, MINNESOTA, A COPARTNERSHIP CONSISTING OF JOEL E. GREGORY,
ESTHER SOPHIA STRAND, AND SAID BERNARD T. PENNIG.

MAIL BOX.

Application filed September 22, 1922. Serial No. 589,877.

To all whom it may concern:

Be it known that I, BERNARD T. PENNIG, a citizen of the United States, residing at St. Paul, in the county of Ramsey and State of Minnesota, have invented certain new and useful Improvements in Mail Boxes; and I do hereby declare the following to be a full, clear, and exact description of the invention, such as will enable others skilled in the art to which it appertains to make and use the same.

My present invention relates to mail boxes adapted to be applied to or built within the walls of residences, offices and other buildings, and is designed particularly as an improvement on the mail box disclosed and claimed in my prior Patent #1,423,251, of date July 18, 1922.

Generally stated, the present invention consists of the novel construction, arrangement and combinations of parts hereinafter described and defined in the claims. More specifically stated, the invention is directed to a feature that makes the box adjustable to walls of different thickness, such, for example, as walls built with four-inch or six-inch studding. This is accomplished by extremely simple and efficient means, the preferred form of which is illustrated in the accompanying drawings, wherein like characters indicate like parts throughout the several views.

Referring to the drawings:

Fig. 1 is a front elevation showing the complete box;

Fig. 2 shows the box positioned in a wall, said box being sectioned on the line 2-2 of Fig. 1;

Fig. 3 is an oblique transverse section taken on the line 3-3 of Fig. 2; and

Fig. 4 is a fragmentary vertical section taken on the line 4-4 of Fig. 2.

The mail box 5 is in the form of a vertically elongated shell made rectangular in horizontal cross-section and preferably made out of galvanized sheet iron. This box will be of a thickness and width adapting it to go into space between the walls and studding of a wall structure having 2" x 4" or even more narrow studding, and at the lower end of the inner wall, said box has a rectangular opening reinforced by a rectangular marginal flange 6 that extends nearly or quite through the inner wall *a* of the wall

structure and registers with ends secured to a rectangular inside door frame 7 to which an outlet door 8 is hinged at its upper edge.

To provide for expansion or adjustment to walls of different thicknesses, the box 5, in the upper portion of its outer wall, is provided with an oblique slidably adjustable intake spout 9, also preferably made of galvanized sheet iron and made rectangular in cross-section. This adjustable spout 9 is held for sliding movements in the upper

portion of the mail box by a spout guide made up, as shown, of an oblique extension 10 and a transverse guide bar 11 of the box 5. The said extension 10 is formed by an oblique upward continuation of the outer wall of the box 5 and by forwardly extended portions of the side plates of said box. The

guide bar 11 is obliquely set so that it engages the oblique top of the spout 9 and, at its ends, is soldered or otherwise rigidly secured to the sides of the box. Also, the sides of the box are preferably provided with angular guide cleats 12 that extend obliquely downward from the bar 11 and assist in holding the spout 9 for straight-line adjustments with its outer edge always in a vertical plane.

The outer edge portion of the spout 9 is in the form of a rectangular marginal flange that extends through the outer wall *b* of the wall structure and is rigidly secured to a rectangular outside marginal door frame 13, preferably by screws 14, the heads of which are on the inner side of said frame 13. An inlet door 15 is hinged at its upper edge to the upper portion of the frame 13 by a hinge rod 16 and is arranged to swing into the spout 9. A torsion spring 17, applied around the rod 16 and anchored at one end to the frame 13 and at its other end to the door 15, yieldingly holds said door normally closed.

In applying the box in a wall, the body thereof will be anchored against the inside wall *a* and then the spout 9 will be adjusted so as to bring the outside door frame 13 to the proper position at the exterior of the outer wall *b*. Then the spout may be rigidly secured in its set adjustment by suitable means, such as a small nut-equipped bolt 18 passed through a perforation in the guide bar 11 and through a slot in the upper plate of the spout 9.

In Fig. 2, the box is shown as applied in a

thin wall structure, such as made where 2" x 4" are used, but when the box is applied in a thicker wall structure, there will be space between the outer wall *b* and the outside wall of said box. Obviously, the adjustable spout makes it an easy matter to adjust the box to wall structures of different thicknesses and makes it unnecessary for the manufacturer to make and carry in stock a large number of different types of boxes.

What I claim is:

1. A mail box adapted to be mounted between the inner and outer walls of a building, provided at the lower portion of its inner wall with an outlet opening and having at the upper portion of its outer wall an adjustable portion formed with an inlet opening, said adjustable portion of the mail box having at its inlet opening a marginal flange equipped with outstanding apertured ears, and a door-equipped door frame capping the marginal flange on the adjustable portion of the mail box, and screws loosely extended through said ears and having threaded engagement with the door frame.
2. A mail box adapted to be mounted between the inner and outer walls of a building, provided at the lower portion of its inner wall with an outlet opening and having at the upper portion of its outer wall and below the top thereof an outstanding oblique spout guide and, working in said spout

guide, an oblique spout that is obliquely adjustable and is formed with an inlet opening, the outlet of said spout being in the body of the mail box.

3. A mail box adapted to be mounted between the inner and outer walls of a building, provided at the lower portion of its inner wall with an outlet opening and having at the upper portion of its outer wall an oblique spout guide and, working in said spout guide, an oblique spout that is obliquely adjustable and is formed with an inlet opening, and clamping means for securing said spout to said spout guide in different adjustments.

4. A mail box adapted to be mounted between the inner and outer walls of a building, provided at the lower portion of its inner wall with an outlet opening and having at the upper portion of its outer wall an oblique spout guide and, working in said spout guide, an oblique spout that is obliquely adjustable and is formed with an inlet opening, said spout having a rectangular outwardly extended marginal flange, a rectangular marginal frame secured to said flange, and a hinged door applied to said frame and normally closing the inlet opening.

In testimony whereof I affix my signature.

BERNARD T. PENNIG.
